UNITED STATES PATENT OFFICE.

RICHARD W. BURNETT, OF CHICAGO, ILLINOIS.

CAR-ROOF.

1,265,738.

Specification of Letters Patent. Patented May 14, 1918.

Application filed June 29, 1917. Serial No. 177,689.

To all whom it may concern:

Be it known that I, RICHARD W. BURNETT, a citizen of the United States of America, residing at Chicago, in the county of Cook 5 and State of Illinois, have invented certain new and useful Improvements in Car-Roofs, of which the following is a specification, reference being had therein to the accompanying drawings.

10 The invention relates to car-roofs of that type in which the roofing sheets are weather-proofed by the carlines and are supported to lie beneath the same, the subject matter being related to that of my co-pending application, Serial Number 177,690. The present invention has particular reference to the means employed for supporting the sheets, permitting of readily engaging and disengaging the same.

15 In the drawings:

Figure 1 is a cross-section through the carlines and portions of adjacent sheets which are weather-proofed and supported by the carlines;

20 Fig. 2, 3, 4 and 5 are similar views showing modified constructions.

25 A is a carline which is of an inverted channel or U-shaped cross-section, preferably provided with the laterally-extending base flanges B. C are the roofing sheets which are arranged to extend beneath the carline and which are provided with upwardly-extending side flanges D engaging the channel thereof.

30 35 To support the sheets each of the flanges D is provided with a laterally-extending portion E, preferably slightly returnbent, as indicated at F. G are clips secured at intervals to the carline within the channel 40 thereof and having downwardly and laterally-extending portions H and I for engaging the laterally-extending portions E of the sheets and constituting a shelf or support therefor. The clips G may be secured in various ways within the carline, such as shown in the several figures of the drawings, Fig. 1 illustrating a depending hanger-bolt J passing through an aperture in the plate and supporting the same by a

45 key K and spacer-sleeve L. Fig. 2 differs from Fig. 1 in that the hanger-bolt J of the former is welded or otherwise secured to the top of the carline, whereas in Fig. 2 the bolt J' is headed and is supported on a 55 shelf or bracket M extending across between the sides of the carline. In Fig. 3 the bolt

J² passes through an aperture in the top of the carline and has a recessed head N for engaging an annular flange O about the bolt aperture to form a weather-proof joint. 60 With all of the constructions thus far described the sheets may be engaged with their supports by removing the sleeve L and supporting key therefor, engaging the clips G with the laterally-extending portions E and 65 sleeving said clips upon the bolts and raising the same to proper position. The sleeves L may then be placed in position and locked by the key K and when secured will perform the double function of supporting the clips 70 and spacing the flanges D.

In the modified construction shown in Fig. 4 the clip G' is spot-welded or otherwise directly secured to the inner top face of the channel carline A, and the flanges D 75 of the sheets are moved upward in the space between the shelf flanges I of the clip and then are moved laterally into engagement with said flanges. Disengagement is prevented by bending downward between the 80 flanges D a lug Q of the clip, which will act as a spacer.

My improved construction is particularly adapted for permitting flexure of the roof to compensate for distortions in the roof 85 frame. Thus each of the sheets is free to move relative to the frame and to the other sheets and at the same time it is securely supported and weather-proofed. The laterally-extending portions F of the upstanding flanges are preferably returnbent as 90 shown, which in addition to increasing the security of the engagement with the clips will form a guard for obstructing the driving of rain over the flanges and into the car. 95

In the modified construction shown in Fig. 5 in place of a single clip I have arranged laterally-extending shelf flanges I' which are secured to the carline by suitable means such as the flange I² welded or otherwise secured thereto. The roofing sheets are of the same construction shown in the other figures and engage the shelf flanges I' in the same manner as the portions I.

What I claim as my invention is:

1. In a car-roof, the combination with inverted channel carlines, of roofing sheets having upstanding side flanges housed within the channel of the carline and laterally and outwardly extending portions at their 110 upper ends, clips having depending and inwardly-turned portions for engaging and

supporting the outwardly-turned portions of the sheet, and spacing means between the upstanding flanges of the sheets for holding the same in engagement with their supports.

5. 2. In a car-roof, the combination with an inverted channel carline, of roofing sheets having upstanding flanges housed within the channel of the carline and provided with laterally and outwardly extending portions 10 at the upper ends of said flanges, clips within the channel of the carline having depending portions at the opposite ends thereof terminating in lateral and inward extensions forming supports for the outward extensions 15 of said flanges, and spacing means between the flanges of said sheets for retaining the same in engagement with their supports, the removal of said spacing means permitting engagement and disengagement of said sheets 20 and their supports.

3. In a car-roof, the combination with an inverted channel carline, of roofing sheets having upstanding side flanges housed within the channel of the carline, the upper ends 25 of said sheets terminating in laterally and outwardly extending portions, a hanger secured to the carline and depending between the upstanding flanges of the sheets, a clip apertured to be sleeved upon said hanger 30 and provided at its opposite ends with depending and inwardly-turned portions for engaging and supporting the outwardly-turned portions of the sheets, and means sleeved upon and detachably supported by 35 said hanger for supporting said clip and forming a spacer between said flanges to retain the same in engagement with their supports.

4. In a car-roof, the combination with an 40 inverted channel carline, of roofing sheets having upstanding flanges terminating in outwardly-extending returnbends or hooks,

a clip secured within the channel of the carline having at its opposite ends downwardly-extending returnbent hooks for engaging 45 and supporting the hooks of said sheets, and removable spacing means between the flanges of said sheets for retaining said hooks in engagement.

5. In a car-roof, the combination with an 50 inverted channel carline, of roofing sheets having upstanding flanges housed within the channel of the carline, said flanges terminating in laterally, outwardly extending portions, a hanger-bolt supported within 55 the channel of the carline and depending between the flanges of said sheets, a clip apertured to be sleeved upon said hanger-bolt and provided with depending inwardly-extending portions at its opposite ends for 60 engaging the laterally-extending portions of said flanges, a tubular spacer sleeved upon said hanger forming a shoulder for supporting said clip and a spacer between 65 said flanges for retaining the same in engagement with the clip, and means detachably engaging said hanger for supporting said tubular sleeve.

6. In a car-roof, the combination with an 70 inverted channel carline, of a roof sheet having an upstanding flange terminating in an outwardly-extending hook, and a shelf supported by the carline on which said flange rests.

7. In a car-roof, the combination with an 75 inverted channel carline, of a roofing sheet having an upstanding flange terminating in an outwardly-extending returnbend or hook, and a shelf extending laterally within the channel of the carline forming a support for 80 said hook flange.

In testimony whereof I affix my signature.

RICHARD W. BURNETT.
